(57) **CLAIM**

The ornamental design for an electronic camera, as shown and described.

DESCRIPTION

FIG. 1 is a top, rear and side perspective view of an electronic camera showing my new design;

FIG. 2 is a rear elevational view thereof;

FIG. 3 is a bottom plan view thereof;

FIG. 4 is a top plan view thereof;

FIG. 5 is a side elevational view thereof from the right of FIG. 2; and,

FIG. 6 is a side elevational view thereof from the left of FIG. 2.

The portions of the camera in broken lines are shown to illustrate environment only and form no part of the claimed design.
